UNITED STATES PATENT OFFICE.

FRANK H. COOK AND CARLTON C. STANNARD, OF LEOMINSTER, MASSACHUSETTS; SAID STANNARD ASSIGNOR TO SAID COOK.

CUTTING AND EMBOSsing DEVICE.

1,072,915.

Specification of Letters Patent.

Patented Sept. 9, 1913.

Application filed May 16, 1910. Serial No. 561,729.

To all whom it may concern:

Be it known that we, FRANK H. COOK and CARLTON C. STANNARD, of Leominster, in the county of Worcester and State of Massachusetts, have invented certain new and useful Improvements in Cutting and Embossing Devices, of which the following is a specification.

This invention has relation to machines for making combs and barrettes for personal wear, and more particularly to those machines which comprise a punch, a die and an ornamenting plunger located in the die and yieldingly supported so as to be depressed below the surface of the die when the punch is operated to cut the blank, and to rise, when the plunger rises, to eject the blank from the die. In such machines the die is provided with a removable section, which when in place completes the shearing edge of the die, so that a barrette may be cut from the sheet of celluloid or other material, and which when removed forms a gap in the shearing edge to leave uncut that portion of the comb blank from which the teeth project.

The present invention provides a novel construction by which the play of the plunger may be varied so as accurately to locate the face of the plunger, when it is raised in a desired plane. It also provides for ornamenting the comb blank in areas outside the face of the plunger, as will subsequently be explained in detail.

Referring to the accompanying drawings, Figure 1 represents in perspective view a mechanism embodying the invention, and arranged to make barrette blanks. Fig. 2 represents a plan view of the same with the punch removed. Fig. 3 represents a longitudinal vertical section through the mechanism. Fig. 4 represents a perspective view of the block plate. Fig. 5 represents a perspective view of the mechanism with the removable section displaced so that a comb blank may be made. In this figure the plunger is shown as removed from the guide pins. Fig. 6 shows the removable section of the die. Fig. 7 represents a plan view of the die with the removable section displaced. Figs. 8 and 9 represent vertical transverse sections through the parts and illustrate the operation thereof on the work. Fig. 10 illustrates a comb blank.

Referring to said drawings, there is illustrated at A what may be termed a base, upon which is secured by screws b or other fastenings a die block. This die block consists of two separable plates or portions c and d one superimposed upon the other. The die block is recessed to receive a plunger e which fits accurately therein, and the face of which is engraved or ornamented so that when the blank is forced upon it, said blank will have the ornamental figures or designs impressed thereon. The edge of the die block plate c surrounding the aperture therein forms a shear or cutting edge with which co-operates the punch f supported by and detachably secured to the under face of a cross head g guided up and down by pins h projecting upwardly from the die block.

The base A and the plunger e are provided with sockets d² e² respectively to receive helical compression springs i upon which the plunger rests and by which it is supported, there being naturally a space between the plunger and the base to permit of the depression of the plunger in the operation of the machine.

In order that the upward play of the plunger may be limited and the face of the plunger accurately located with respect to the face of the die, the plunger is provided with pins or projections e² e² extending from its ends and lying in vertical slots or grooves d' d' formed in the die block plate d as shown in Figs. 3 and 4. The plate c is unslotted, and through it are passed two vertical adjusting screws c' c' whose lower ends engage said pins or projections e² e². By reason of this construction the upper surface of the plunger may be leveled, or the plunger may be adjusted bodily up and down without removing the die block from the base or removing the die block and its base from the press, since the slotted ends of the screws are accessible from above the die block.

The die block plate c is provided with a removable section j, which, when barrettes are to be made, fits accurately in a recess c³ formed in the upper face of said plate, when the section is removed as shown in Fig. 5, the end walls c⁴ of the recess c³ form shearing or cutting edges, which co-operate with complementary edges f' f' on an extension f² on the punch which is employed for forming the combs.

The bottom of the recess may be engraved or otherwise ornamented for the purpose of ornamenting that portion of the blank which is outside the plunger, when the blank is pressed against it by the punch. For example, the plate *c* is formed with a raised rib *c*⁵ which is curved to conform to the outline of the plunger-receiving aperture in the die block so as to form a sinuous groove in the face of the blank. In addition scroll work and other ornamentation may be formed on the bottom of the recess as may be desired. In this particular case the removable section *j* is slightly recessed on its under face near its inner edge as indicated at *j'* so as to receive the raised rib *c*⁵. Any suitable means may be utilized for securing the removable section in place. As illustrated the section is provided with dowel pins, *j*² which fit in apertures *c*⁶ in the die block and is also provided with apertures *j*³ to receive screws or other fastenings which are fast in their apertures *c*⁷ in the die block. In operation the die block, its base and the punch are placed in a suitable stamping press in which the cross-head *g* and its stem *g'* are actuated by the usual means.

Having thus explained the nature of our said invention and described a way of constructing and using the same, although without attempting to set forth all of the forms in which it may be made or all of the modes of its use, we declare that what we claim is:—

1. In a cutting and embossing device, a die block having a plunger-receiving recess in its top face, a punch, a spring-sustained plunger in said die block having projections extending beyond its operative face, and

adjusting means accessible from the top of 40 said block and engaging said projections.

2. In a cutting and embossing device, a punch, a two part die block having a plunger-receiving recess in its top face, a spring-sustained plunger located in said recess and 45 deppressible therein, said plunger having projections, and adjusting devices supported by the upper part of said block and engaging said projections.

3. In a cutting and embossing device, the 50 combination with a punch adapted to descend upon the work, of a die block on which the work may be placed, said die block having in its top face a recess, a plunger in said recess, cushioning means below the plunger 55 for forcing it upward, projections on said plunger beyond the area of its upper face, and adjustable stops accessible from the top of said die block and adapted to be engaged by said projections for limiting the upward 60 movement of said plunger.

4. In a cutting and embossing device, a punch, a die block having a plunger-receiving recess, and comprising two separable plates, one superimposed upon the other, the 65 lower plate having slots or grooves, a spring sustained plunger located in said recess and having projections extending into said grooves or slots, and adjusting screws passed downwardly through the upper plate of said 70 die block to engage said projections.

In testimony whereof we have affixed our signatures in presence of two witnesses.

FRANK H. COOK.

CARLTON C. STANNARD.
